COMBINED MOP AND MOP WRINGER

John W. Tatter, Detroit, Mich., assignor, by
mesne assignments, of one-half to Ella I.
Ingersoll, Dearborn, Mich.

Application December 28, 1929
Serial No. 417,074

18 Claims. (Cl. 15—120)

My invention relates to improvements in mops combined with wringer means; and the objects of my improvements are, first, to provide a mop capable of being remotely operated in its wringing action with a minimum of applied energy; second, to provide a mop having a readily replaceable mop element; third, to provide a mop capable of efficiently presenting its mop element to the surface to be mopped irrespective of the height of the operator; fourth, to provide a mop capable of presenting its mop element to the surface to be mopped in a crosswise direction to the strands of its mop element; fifth, to provide a mop element with transversely placed means for wringing said mop element from both of its ends; sixth, to provide a mop element with means for wringing efficiently in lesser time than with the usual means; seventh, to provide a mop wringing means automatically locked from movement by the pressure application of the mop against the surface to be mopped; eighth, to provide a mop capable of being entered easily into spaces of restricted area; and ninth, to provide a mop wringing means having power transmission reduction members enclosed in a housing adjacent the mop element.

I attain these objects by the mechanism illustrated in the accompanying drawings, in which—

Figure 1 is a side elevation of the combined 30 mop and wringer means when in its usual operating position relative to the surface to be mopped; Fig. 2, a side elevation of the mop in its wrung position and being withdrawn from a pail; Fig. 3, a plan elevation of the mop in its 35 wrung position and being withdrawn from a pail; Fig. 4, a side elevation of the lower end of the mop and the mop element, the mop element being shown in a depending position relative to its wringing means; Fig. 5, an end elevation of the 40 mop and the mop element, the mop element being shown in a depending position relative to its wringing means; Fig. 6, a plan elevation of the mop and the mop element, the mop element being 45 shown in a depending position relative to its wringing means; Fig. 7, a sectional view taken on the line 7—7, Fig. 4; Fig. 8, a sectional view taken on the line 8—8, Fig. 7, said view being taken with one of the side gears removed; Fig. 9, 50 a side elevation of one of the locking members; Fig. 10, an end elevation of one of the locking 55 members; and Fig. 11, a view showing the mop element retaining means in its partially disconnected position for receiving or removing the mop element.

Similar numerals refer to similar parts throughout the several views.

The housing portions 1 and 2 are preferably, made as duplicate parts which may be fastened together by the screws 3 to form a closed end 60 housing which fits over the end of the handle 4 and is fastened thereto by the screws 5. Each of the screws 3 pass through one of the housing portions 1 and 2 and are threaded into the other of the housing portions 1 and 2, thus rendering possible 65 the use of duplicate parts for the housing portions 1 and 2. The handle 4 is disclosed as being made of wood but it may be made of metal or other suitable material. Each of the housing portions 1 and 2 is made with a spherical seat 70 6 which forms a bearing seat for the spherical surface 7 on each of the gears 8 which are thus located on opposite sides of the pinion gear 9 with which they mesh and operate by means of the gear teeth 10 on the pinion gear 9 and the gear teeth 11 on the gears 8. The pinion gear 9 is suitably connected to and provided with the extension portion 12 which has a bearing in the housing portions 1 and 2, said extension portion 75 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840

Each of the gears 8 are further provided with shaft extensions 17 which extend through and may have a bearing seat in the walls of the housing portions 1 and 2. The shaft extensions 17 105 are thus revolvably operated with the gears 8. It is to be noted that one of the gears 8 is provided with a pilot portion 18 which enters and seats within a recess 19 in the other of the gears 8. In each end of the shaft extensions 17, a loop 110

member 20 is mounted to provide retaining means for the mop element 21. The mop element 21 is composed of a suitable number of twisted fibrous strands 22 which are suitably fastened together to form looped portions 23 through which is inserted the looped members 20. The looped members 20 are formed to allow each of their ends to pass through and seat within holes 26 in each of the shaft extensions 17. It is to be noted that each of the shaft extensions 17 are provided with suitable grooves 24 and 25, as shown in Fig. 11, and in which is seated the lock member 27 when the looped members 20 are in their operating positions, as shown in Figs. 1, 4, 5, and 6. One end of each of the looped members 20 is formed with a retaining shoulder 28 which prevents each of the looped members 20 from being displaced through the shaft extensions 17 in one direction while the lock member 27 engages the grooves 24 and 25 of the looped members 20 and prevents the looped members 20 from being displaced through the shaft extensions 17 in an opposite direction. The lock member 27 may be constructed of resilient material having its fingers 30 always tending to pinch the bottom of the grooves 24 and 25 in the looped members 20 thus providing a safety lock feature.

Whenever it is desired to remove or replace a mop element 21, the lock member 27 is slidably operated out of the grooves 24 and 25 in the looped members 20, thus allowing the looped members 20 to be slidably displaced in the holes 26 to the position shown in Fig. 11, where one end 31 of the looped member 20 is free of the shaft extension 17, thus allowing the looped portion 23 of the mop element 21 to be slipped over the looped member 20 to its operating position after which the end 31 of the looped member 20 is passed through one of the holes 26 thus allowing the looped member to again assume a position where it may be restrained in its operating position by inserting the lock member 27 in the grooves 24 and 25. It is to be noted that the loop members 20 are formed with a curved base portion 29 which allows the operator to rock or rotate the combined mop unit on the floor or the surface 33 to be mopped so that the desired angular position of the handle 4 and the shaft 16 may be automatically selected, as desired, to best suit the height of the operator. Also in the forward and return operating movements of the combined mop, the rocking or rotating movement will always allow the operator to automatically present the mop element most efficiently to the surface to be mopped.

It is to be noted that the looped members 20 may be formed, relative to the holes 26 in the shaft extensions 17, to provide any desired angular operating position relative to the floor line, a normal angular operating position being shown in Fig. 5. Any variation of the angular operating position of the looped members 20, relative to the holes 26 in the shaft extensions 17, will provide a greater or lesser spread on the floor or surface 33, thus providing, if desired, for the use of varying lengths of mop elements 21 for particular purposes. It is to be noted that my mop provides for the retention of the mop element 21 against the surface to be mopped in a manner which allows the thrust load of the operating mopping movements to be taken transversely on each of the strands 22 of the mop element 21. This enables each strand 22 to more efficiently engage the surface to be mopped by

causing each strand 22 to be moved individually and collectively in a sideways movement across the surface to be mopped as contrasted with the usual inefficient method of moving the strands lengthwise along the surface to be mopped, each strand of the latter case being restricted, in the main, to a path having a width approximately equal to its diameter or width whereas in the former case, as disclosed by my invention, each strand has a mopping path approximately equal to its total working length.

It is also to be noted that in the actual mopping operation, the strands 22 of the mop element 21 tend to be crowded between the looped members 20 and about the rounded end of the closed end housing of the housing portions 1 and 2, thus retaining the mop element in a compact and efficient mopping position and preventing the formation of straggling portions of the mop element 21. Also the closed end of the housing portions 1 and 2 when surrounded by the strands 22 of the mop element 21 will provide means for maintaining the center portions of the strands 22 in a more efficient mopping position and will prevent a portion of the strands 22 from being unduly stretched by the thrust of the frictional contact with the surface 33 when being moved to and fro in operation, the strands 22 being engaged and backed up by contact against the outside surface of the closed end of the housing portions 1 and 2. After the mop element 21 has become saturated with water or moisture in the mopping operation, it can be readily removed to a position over a pail or receptacle 34 as shown in Figs. 2 and 3, where the mop element can be easily wrung dry by exceptionally light hand pressure applied to the hand grip portion 16 of the shaft 15. With one hand of the operator grasping the handle 4 and the other hand of the operator grasping the hand grip portion 16, the shaft 15 can be revolved, the tongue 14 of the shaft 15 engaging the slot 13 in the extension portion 12 of the pinion gear 9 and thereby causing the pinion gear to revolve together with the gears 8. It is to be especially noted that, as the pinion gear 9 is revolved in one direction, each of the gears 8 together with their respective shaft extensions 17 and looped members 20 are revolved in opposite directions thus winding up and wringing dry the mop element 21 as shown in Figs. 2 and 3.

The revolving of the gears 8 together with their respective shaft extensions 17 and looped members 20 in opposite directions cause a wringing action to be most efficiently applied to each end of the mop element 21 thus not only providing an efficient means of wringing but a much quicker means of wringing than usually employed in designs in which the mop element is anchored at one end and twisted from one of its ends only. Also it is to be noted that, by the adoption of the proper gear ratios between the pinion gear 9 and the oppositely revolving gears 8, a means is provided whereby the mop element can be efficiently wrung dry by extremely light pressures applied by the operator to the hand grip portion 16 of the shaft 15. My invention will very noticeably relieve the difficult and disagreeable operation encountered in the wring-means of mops of the usual construction and design.

It is also to be noted that the efficient wringing action of my invention is increased by the smooth and spherical exterior shape of the closed end of the housing portions 1 and 2 which allow the strands 22 of the element 21 to be most efficiently wrapped therearound as shown in Figs. 2 and 3.

It is to be noted that the compact shape and size of my invention will allow for the use of smaller pails or receptacles 34 than with the usual type of mop and its wringer means, this feature being disclosed in Fig. 3. Also the design of my invention will allow for its efficient use in mopping in and around places of restricted area and by its shape will allow for efficient use adjacent objects resting on the floor such as the supports and legs 10 of furniture and household appliances.

I claim:

1. In a combined mop and mop wringer, the combination of a hollow longitudinal member, housing members attached together and to said 15 hollow longitudinal member, said housing members being each provided with spherical seats laterally disposed relative to said hollow longitudinal member, a pair of members each provided with a spherical surface for engaging the spherical seat of one of said housing members, each of 20 said pair of members having portions extending through said housing members, said portions being laterally disposed relative to said hollow longitudinal member, an absorbent element, means 25 for attaching said absorbent element to the portions of each of said pair of members extending through said housing members, a member for engaging and causing each of said pair of members to operate in opposite directions, and means 30 for operating said last member, said last mentioned means extending within said hollow longitudinal member.

2. In a mop wringer, the combination of a housing provided with a handle portion, a pair 35 of reduction gear members in said housing, said pair of gear members being located within said housing on an axis extending transversely to the handle portion of said housing, a pair of shaft members extending outwardly beyond said pair 40 of gear members and said housing, each of said pair of shaft members being connected to one of said pair of gear members, and means for simultaneously revolving said pair of gear members in opposite directions about their trans- 45 versely extending axis, said means being located between said pair of gear members and on the longitudinal axis of the handle portion of said housing.

3. In a mop and mop wringer, the combination 50 of a handle member, a housing suitably supported at the end of said handle member, a pair of gear members within said housing, each of said gear members being provided with portions extending on opposite sides of said handle member, a mop element connected to the portions 55 of said gear members extending on opposite sides of said handle members, and a handle member for operating said gear members in opposite directions to cause the ends of said mop element 60 to revolve in opposite directions, said handle member being provided with a gear member for engaging said pair of gear members, said last mentioned gear member being located on the longitudinal centers of said first mentioned handle member and said second mentioned handle member.

4. In a combined mop and mop wringer, the combination of a handle, members extending outwardly from opposite sides of said handle, a 70 mop element having ends oppositely disposed about said handle, the ends of said mop element being supported by said members in an approximately common transverse plane relative to said handle, and means for revolving said members and the ends of said mop element in opposite di-

rections about an axis extending transversely to the longitudinal axis of said handle.

5. In a combined mop and mop wringer, the combination of a mop element, a pair of concentric handle members extending approximately at right angles to said mop element, and means for revolving each end of said mop element in opposite directions about an axis extending approximately transversely to the longitudinal axes of said handle members, said means being connected to the opposite ends of said mop element, said means being operatively connected with one of said handle members.

6. In a combined mop and mop wringer, the combination of a pair of concentric handle members, a housing at the extreme end of one of said handle members, mop supporting members extending through said housing and about an axis extending approximately at right angles to said handle members, a mop element having its ends connected to opposite ends of said mop supporting members, a pair of gear members suitably mounted in said housing, said pair of gear members in said housing being located on opposite sides of the longitudinal axes of said handle 100 members, said pair of gear members being operatively connected with said mop supporting members, and a gear member located between and engaging said pair of gear members, said gear member being operatively connected with one of said handle members.

7. In a mop and mop wringer, the combination of a handle, mop supporting members revolvably mounted on an axis extending approximately at right angles to said handle, a mop 110 element having its ends attached to the outer ends of said mop supporting members, and means for revolving the opposite ends of said mop supporting members and said mop element in opposite directions about the axis of said mop supporting members, said means including a revolvably mounted handle member extending concentric with said first mentioned handle.

8. In a mop and mop wringer comprising a main handle portion, the combination of rotatably mounted members supported by the handle portion, each of said rotatably mounted members being provided with a portion offset relative to its axis, a mop element extending transversely to the longitudinal center of the main handle 125 portion of the mop and mop wringer, said mop element being connected to the offset portion of said rotatably mounted members, and means for revolving each of said rotatably mounted members together with its offset portion in opposite directions, each of the offset portions of said rotatably mounted members thereby being revolved in a plane extending parallel with the longitudinal center of the main handle portion of the 130 mop and mop wringer.

9. In a mop and mop wringer, the combination of a handle member revolvably mounted, a pair of mop retaining members extending on opposite sides of said handle member, each of said 140 mop retaining members including a gear member, a mop element having its ends supported, in its mopping position, by the outer end portions of said mop retaining members, and a gear member suitably mounted between and engaging the gear 145 members of said mop retaining members, said last mentioned gear member being operatively connected with said handle member, said last mentioned gear member and said gear members of said mop retaining members operating to re- 150

volve each end of said mop element in opposite directions.

10. In a mop and mop wringer, the combination of a mop element, a handle member extending in a plane approximately at right angles to said mop element, said handle member extending longitudinally to the upper end of the mop and mop wringer, a pair of mop supporting members suitably mounted to revolve about a common axis extending approximately at right angles to said handle members, said mop supporting members being connected to said mop element, and means for revolving said mop supporting members in opposite directions, said means being operatively connected with said handle member.

11. In a mop and mop wringer, the combination of a mop handle, a pair of oppositely disposed gear members each provided with an outwardly extending portion, said outwardly extending portion extending transversely to said mop handle, a mop element suitably connected with the outwardly extending portion of each of said pair of gear members, said mop element being disposed parallel with the extensions of said pair of gear members, said mop element being further disposed transversely to said mop handle, and means for operating each of said pair of gear members in opposite directions.

12. In a mop and mop wringer, the combination of a housing having a main handle portion, a revolvably mounted member in said housing, said revolvably mounted member having a handle portion extending longitudinally through the first mentioned main handle portion of said housing, a pair of arms suitably mounted in said housing, said pair of arms extending in a common transverse plane relative to the first mentioned main handle portion of said housing, said pair of arms being engaged by said revolvably mounted member in said housing, and a single mop element extending transversely to the first mentioned handle portion of said housing, said mop element having its ends suitably connected to the outer ends of said pair of arms, said mop elements having its ends located approximately in a single transversely extending plane.

13. In a mop and mop wringer, the combination of a handle, a housing connected to one end of said handle, a pair of gear members in said housing, said gear members each being provided with a member extending through one of the sides of said housing, a mop element connected to the extending members of said pair of gear members, and means for revolving said pair of gear members in opposite directions to cause said mop element to be forced into contact with said housing, said means including a gear member, engaging said pair of gear members.

14. In a mop and mop wringer, the combination of a pair of concentric handles, one of said pair of concentric handles being revolvably mounted, and a mop element extending longitudinally in a transverse direction relative to the longitudinal axis of said pair of concentric handles, said mop element having both of its ends operatively con-

nected with the revolvably mounted handle of said pair of concentric handles, to provide a wringing movement of each of its ends.

15. In a mop and mop wringer, the combination of concentric handle members, a mop element extending transversely to the longitudinal axes of the concentric handle members, means for supporting the ends of said mop element on opposite sides of the longitudinal axes of said concentric handle members, and means for revolving the ends of said mop element in opposite directions, said last mentioned means being operatively connected with said first mentioned means and one of said concentric handle members.

16. In a mop and mop wringer, the combination of a revolvably mounted handle, a pair of revolvably mounted members each provided at one of their ends with a curved base portion extending in a plane at an angle with said revolvably mounted members, said revolvably mounted members having a common axis extending approximately at right angles with said handles, said curved base portions being located on opposite sides of the axis of said revolvably mounted handle, a mop element extending between the curved base portions of said pair of revolvably mounted members, and means for revolving each of said pair of revolvably mounted members together with their curved base portions in opposite directions about the common axis of said revolvably mounted members, said means being operatively connected with said pair of revolvably mounted members and said revolvably mounted handle.

17. In a mop and mop wringer, the combination of a pair of concentric handle members, a pair of revolvably mounted members each provided with a mop attachment portion at one of their ends, the mop attachment portion of each of said pair of rotatably mounted members being supported on opposite sides of the axes of said concentric handles and in oppositely inclined positions relative to one another when the mop and mop wringer is in its mopping position, said pair of rotatably mounted members having a common axis extending approximately at right angles to the axes of said concentric handles, a mop element connected to the mop attachment portions of each of said rotatably mounted members, and means for revolving said pair of rotatably mounted members in opposite directions, said means being operatively connected with one of said concentric handles.

18. In a mop and mop wringer for mopping a flat surface, the combination of a handle, a pair of spaced mop retaining members, said mop retaining members being spaced on opposite sides of said handle, each of said mop retaining members being provided with a portion extending adjacent the flat surface to be mopped, a mop member attached to and extending between said pair of spaced mop retaining members, and means for revolving said mop retaining members in opposite directions.

JOHN W. TATTER. 140
